UNITED STATES PATENT OFFICE.

LOUIS CADENEL, OF PARIS, FRANCE.

ELECTRIC SAFETY COMBINATION LOCK.

Application filed January 15, 1923. Serial No. 612,843.

To all whom it may concern:

Be it known that I, LOUIS CADENEL, a citizen of the French Republic, residing at 7 Rue de Tracy, Paris, France, have invented 5 certain new and useful Improvements in Electric Safety Combination Locks, of which the following is specification.

This invention has for its object to provide a multiple combination electric safety 10 lock, which enables a door to be locked without the use of a key; it being only possible to open and close it when in possession of the secret of the combination.

The figures of the combination can be 15 varied at will by the owner of the lock, and the number of combinations can be as large as is desired.

The cover which has to be removed in order to alter the number can only be so 20 removed when the proper number to which the device is set is known.

In addition, any attempt to open the lock made by a person who is not in possession of the number is immediately signalled by 25 one or more electric bells.

Finally, the lock is adapted to be released from the interior of the apartment by means 30 of a simple electric push, which may be more or less concealed; this arrangement being provided for convenience of the occupant of the apartment.

The accompanying drawings show, by way of example, one method of carrying the invention into practice.

35 In these drawings:—

Fig. 1 shows the interior of the lock and illustrates the various mechanisms, their arrangement and the electric connections.

Fig. 2 is an outside elevation of the lock 40 showing the two knobs for the combinations and the knob for operating the bolt.

Fig. 3 is an elevation of one of the cylindrical commutators on the combination mechanism.

45 Fig. 4 is a plan of the two commutators illustrating the figure controlling devices.

Fig. 5 is a cross section through one of the commutators with its enclosing cover provided with means for preventing the removal of the cover when the figure of the combination is not known.

As will be seen from the two first figures, the whole lock is mounted upon a metallic base plate P, adapted to be attached to the door, which it is required to lock.

The bolt β of the lock slides in guides and

is controlled by the knob A (see Fig. 2) through the rotation of a small toothed wheel b meshing with a rack on the bolt.

The bolt is also provided with two recesses c^1 and c^2 , corresponding to the closed and opened positions, and it is secured in one or other of these positions by means of the movable armature n of an electro-magnet e which drops into one or other of the recesses.

Consequently, the lock cannot be opened or closed unless an electric current is passed through the coil of the electro-magnet e .

For this purpose, the bolt, which constitutes with the base plate P a continuous metallic portion of the apparatus, carries a spring controlled rubbing contact f which is in electrical connection with the metallic casing.

This rubbing contact, when it is desired to open or close the lock, comes into contact with the insulated copper block d which is connected to the contact brush r^1 of the first commutator.

There are two cylindrical commutators, each of which is adapted to take up any one of 8 positions, thus giving 64 possible combinations; if there are N commutators there will be 8^N possible combinations.

Each of these commutators comprises a metallic wheel h^1 or h^2 as the case may be furnished with 8 notches disposed symmetrically around its periphery, and the contact spring R^1 or R^2 provided with a contact stud which is adapted to drop into the notches, is arranged to bear upon the corresponding wheel. The contact stud drops in with sufficient force to be perceptible to the touch and so that it can be heard coming out of engagement when turning the knob a^1 or a^2 . This enables the position of the commutators to be determined by counting the number of clicks without any figures appearing on the exterior of the lock.

The notched wheel h^1 or h^2 is insulated from the main metallic body of the apparatus and is permanently connected electrically with the contact finger i^1 or i^2 as the case may be. The finger turns with the wheel around its axis. g^1 or g^2 is a copper ring, also insulated from the main body and turning with the commutator, at the same peripheral distance as i^1 or i^2 . It has a cut away portion in which is located one of the contact fingers i^1 or i^2 , as the case may be.

The spring brushes r^1 and r^2 bear upon

the cylindrical members carrying the rings and the contact fingers; and there are two other similar spring brushes r^1 r^2 placed diametrically opposite the first mentioned 5 brushes; it is however to be noted that the brushes r^1 , r^2 can never come into contact with the contact fingers i^1 , i^2 .

The contact ring and the contact finger are so relatively spaced that when one of 10 the brushes r^1 or r^2 is in contact with the contact finger i^1 or i^2 the stud of the spring contact R^1 or R^2 drops exactly into a notch in the wheel h^1 or h^2 .

Fig. 3 shows, in elevation the controlling 15 spindle a of the commutator, the insulated wheel h , connected to the insulated finger i , the ring g and the spring contact brushes r , r' , R .

Referring to Fig. 1, it will be seen that the 20 spring contact R^1 of the first commutator is connected to the spring brush r^2 of the second commutator, the spring brushes r^1 and r^2 of the two commutators being connected together and to the terminal 3 of the apparatus. The spring contact R^2 of the second 25 commutator is connected to the plate C which is connected to one of the extremities of the electric coil, whilst the other extremity of the said coil is connected to the 30 terminal 1 of the apparatus.

In addition, the apparatus is provided with the unlocking or releasing handle k which comprises a metallic blade k' which comes normally into contact with an upper 35 contact stud l connected to the metallic casing of the apparatus. The fixed end o of the blade k' is connected to the terminal 2 of the apparatus.

When the handle k is operated, the blade 40 k' is moved from the upper contact l and brought into contact with the lower contact stud q which is connected with the plate C and thence with the electro-magnet.

Between the terminals 1 and 2 is connected 45 as indicated at u the external source of current (battery accumulator, lighting circuit or the like); and with the terminals 1 and 3 is connected the alarm bells s .

With the foregoing construction and arrangement 50 it will be seen that when the brush r^1 bears exactly upon i^1 and r^2 upon i^2 , and the handle A controlling the bolt of the lock is turned, the electric circuit is completed through the following members:—the casing f , d , r^1 , i^1 , h^1 , R^1 , r^2 , i^2 , h^2 , R^2 , C , e , u , the casing. 55

The electro-magnet raises the armature and frees the bolt which can then open or close. In each position, that is when the bolt 60 is open or closed, the rubbing contact f leaves the contact block d and breaks the circuit.

If on the other hand the two brushes r^1 and r^2 or only one of them, is not in contact 65 with the corresponding finger i^1 or i^2 , the

brush or brushes will be in contact with the ring or rings g^1 or g^2 , at the same time as the brushes r^1 and r^2 , so that when the attempt is made to operate the bolt of the lock, the circuit is closed through the bell s which 70 gives an alarm. The current is however not passed through the electro-magnet, so that the lock cannot be opened.

The commutators are thus brought into series for opening the lock and into parallel 75 for giving the alarm in case of an attempt to open the lock.

If a larger number of commutators is provided, in order to increase the possible number of combinations, there is the same 80 underlying principle adopted for connecting them.

At Fig. 4 is shown the manner in which 85 each of the commutators is set into the proper position.

Each of the insulated cylindrical members of the commutators is provided with 8 perforations, v is a stopping finger mounted loosely upon the spindle of the commutator and provided with a pin which is adapted to engage in any one of the 8 perforations, thus determining the position of the stopping finger v with respect to the cylindrical body and consequently with respect to the contact finger i of the commutator. 95

The stopping finger is adapted to come against the stop x either to the right or to the left. This screw stop x determines the initial position of the cylinder from which the owner of the lock calculates the number of clicks desired to obtain the release of the bolt. According to the number of the hole or perforation, which may be chosen arbitrarily for each commutator, a different controlling number and combination 100 will be obtained.

In addition, so that nobody except the owner of the secret of the number can change the number of the combination, or discover it by simply opening the cover D this cover itself, besides being provided with screw means of attachment, is locked in the following manner:—

Each of the commutators is surmounted by a dished portion y shaped as shown at 115 Fig. 5. This is connected to the spindle at the same time as the stopping finger v by means of the screw V but so that it moves in unison therewith.

The dished member y is cut away at Z in such a manner that the hook w on the cover can pass through such cut away portion when it comes opposite thereto.

The hook w , one of which is provided for each commutator is attached to the cover and adapted to engage behind the respective dished member y . 125

In this way, the cover can only be removed when the openings Z of all the commutators come simultaneously opposite to 130

hooks w , and this only occurs in the positions of the commutators corresponding with the number which is utilized for controlling the opening of the lock.

5. As regards the electro-magnet e of the apparatus, it is of special construction in so far that it is provided with a magnetic jacket m , which entirely surrounds the winding.

10. This protects the armature from external fields which might be produced by the use of a magnet, with a view of attempting to release the bolt.

15. t is a perforation through the jacket in order to enable air to pass.

The small armature n^1 which is introduced into a perforation provided in the bolt is intended to take the place of the armature n in a case where by the use of a powerful 20 electro-magnet, an attempt might be made to raise the primary armature to disengage it from the recess c^2 , thus preventing by this secondary means the fraudulent opening of the lock. On the other hand, the lower 25 cheek of the magnet being of somewhat thick iron, the magnetic circuit m does not give the minimum of reductance and gives the maximum of attraction on the armature when the magnet is excited.

30. Finally, in order that the armature n should not stick through the residual induction, either in the upper position or in the lower one, it is provided at each end with a small thickness of copper to form a light 35 intercepting device.

This has for object also to render as rapid as possible the attraction of the armature when f touches d , so that the lower extremity of n shall not jam against the sides of 40 c^1 or c^2 , preventing the movement of the bolt, in spite of the fact that the current is passing around the magnet.

This secret lock with automatic alarm is applicable not only to the doors of apartments, or furniture, but for closing safes 45 and for all apparatus which should not be operated or removed without the knowledge of the owner or of a person responsible for its safety.

50. What I claim and desire to secure by Letters Patent of the United States of America is:—

1. In a safety lock of the type described, the combination of a sliding bolt provided 55 with two recesses, one corresponding to the open, and the other to the closed position of the lock, an electromagnet having a movable armature adapted when current is not passing through the coil of the magnet to engage in either of the said recesses, mechanism for operating the bolt by means of a knob from the outside, a plurality of commutators, each of said commutators being provided with a metallic wheel with symmetri- 60 cally disposed notches around its periphery, the said wheel being insulated from the casing and being carried by a spindle adapted to be operated by means of a knob on the outside, a spring conducting arm provided with a stud adapted to engage the said notches, a conducting finger mounted upon each commutator wheel, an insulated broken ring also mounted upon the said wheel, conducting brushes adapted to come into contact with the said finger and the said ring, means for setting the commutator wheel so that the finger only comes into contact with the corresponding brushes after a determined number of notches of the commutator wheel have been passed, a source of electric energy, an alarm bell and suitable electric connections, so arranged that when the fingers of all the commutators coincide with their contact brushes, the current passes to the magnet to enable the lock to be operated, whilst when both the brushes of a commutator rest upon the conducting ring, the current passes to 130

periphery, the said wheel being insulated from the casing and being carried by a spindle adapted to be operated by means of a knob on the outside, a spring conducting arm provided with a stud adapted to engage the said notches, a conducting finger mounted upon each commutator wheel, an insulated broken ring also mounted upon the said wheel, conducting brushes adapted to come into contact with the said finger and the said ring, means for setting the commutator wheel so that the finger only comes into contact with the corresponding brushes after a determined number of notches of the commutator wheel have been passed, a source of electric energy, an alarm bell and suitable electric connections so arranged that when the fingers of all the commutators coincide with their contact brushes, the current passes to the magnet to enable the lock to be operated, whilst when both the brushes of a commutator rest upon the conducting ring the current passes to the alarm bell and the magnet is not operated, a notched dished disc in connection with the mechanism through which a hook attached to the cover is adapted to pass when the figure combinations are in the correct positions for opening the locks, all substantially as and for the purposes set forth. 95

2. In a safety lock of the type described, the combination of a sliding bolt provided with two recesses one corresponding to the open and the other to the closed position of the lock, an electromagnet having a movable armature adapted when current is not passing through the coil of the magnet to engage in either of the said recesses, mechanism for operating the bolt by means of a knob from the outside, a plurality of commutators, 100 each of said commutators being provided with a metallic wheel with symmetrically disposed notches around its periphery, the said wheel being insulated from the casing and being carried by a spindle adapted to be operated by means of a knob on the outside, a spring conducting arm provided with a stud adapted to engage the said notches, a conducting finger mounted upon each commutator wheel, an insulated broken ring also mounted upon the said wheel, conducting brushes adapted to come into contact with the said finger and the said ring, means for setting the commutator wheel so that the finger only comes into contact with the corresponding brushes after a determined number of notches of the commutator wheel have been passed, a source of electric energy, an alarm bell and suitable electric connections, 105 so arranged that when the fingers of all the commutators coincide with their contact brushes, the current passes to the magnet to enable the lock to be operated, whilst when both the brushes of a commutator rest upon the conducting ring, the current passes to 110

120

125

130

the alarm bell, whilst the magnet is not operated, the bolt of the lock being further provided with a recess containing a secondary electric armature adapted to operate as a secondary locking means, substantially as and for the purposes set forth.

3. In apparatus of the type described, and as claimed in claim 1, the combination therewith of means under the control of the

operator for passing a current through the electromagnet and releasing the lock independently of the combination mechanism, substantially as and for the purposes described.

In testimony whereof, I have hereunto subscribed my name.

LOUIS CADENEL.
